UNITED STATES PATENT OFFICE.

THOMAS B. HYATT, OF CONNELLSVILLE, PENNSYLVANIA.

RESERVE-SUPPLY VALVE.

Specification of Letters Patent.

Patented Mar. 16, 1915.

1,132,350.

Application filed June 5, 1914. Serial No. 843,319.

To all whom it may concern:

Be it known that I, THOMAS B. HYATT, a citizen of the United States, residing at Connellsville, in the county of Fayette and State of Pennsylvania, have invented new and useful Improvements in Reserve-Supply Valves, of which the following is a specification.

This invention relates to improvements in reserve supply valves and has particular application to a valve of this class for the fuel tanks of hydrocarbon engines of motor cars.

In carrying out the present invention, it is my purpose to provide a reserve supply valve whereby the operator of a motor vehicle will be automatically advised when the level of the liquid fuel within the tank supplying the hydrocarbon engine has dropped to a predetermined point so that such operator will be notified of the quantity of fuel within the tank before the latter has been exhausted.

It is also my purpose to provide a device of the class described which will retain a certain quantity of fuel within the tank and enable such fuel to be delivered to the engine after the operator has been advised that the fuel level has dropped to a predetermined point.

With the above and other objects in view, the invention consists in the construction, combination and arrangement of parts hereinafter set forth in and falling within the scope of the claim.

In the accompanying drawing; Figure 1 is a fragmentary vertical sectional view through an automobile supply tank equipped with a reserve supply valve constructed in accordance with the present invention, the valve being shown partly in section and partly in elevation. Fig. 2 is a fragmentary vertical sectional view through a modified form of valve. Fig. 3 is a similar view through a still further modified form of valve.

Referring now to the drawing in detail, 1 designates a liquid fuel tank such as is carried by motor cars for supplying the hydrocarbon engines thereof with fuel, such tank being of any desired capacity. As

usual, the bottom wall of the tank is formed with an outlet opening 2 and leading from such opening to the carburetor of the engine is a supply pipe 3, while formed in the top wall of the tank is a filling opening 4 and threaded into such opening is a closure plug 5. In the present instance, the filling opening aligns axially with the outlet opening 2.

In accordance with my present invention, 60 the plug 5 is hollowed out to provide a chamber 6 and the bottom wall of the chamber is formed centrally with an opening 7, while the side wall of the chamber flares upwardly and outwardly from the bottom wall 65 and is formed at diametrically opposite points with openings carrying filtering screens 8. The upper end of the chamber 6 is open and threadedly engaging the inner wall of the chamber at the open end thereof and closing such end is a cap 9 capable of removal whereby the tank or reservoir may be filled by pouring the liquid fuel into the chamber 6 whence it flows into the tank 70 through the screens 8, thereby trapping any 75 sediment therein.

My improved reserve supply valve comprises a vertical tube 10 arranged within the tank 1 and having the lower end thereof screw threaded as at 11 and passed through the outlet opening 2 and threaded into the adjacent end of the supply pipe 3 and the upper extremity thereof terminating a short distance above the bottom wall of the tank. Formed in the tube 10 immediately above the bottom wall of the tank or reservoir are one or more openings 12. Arranged within the tank 1 coaxial with the tube 10 is a second tube 13 having the lower end thereof telescoping within the tube 10 and the upper portion thereof screw threaded as at 14 and threaded through the opening 7 in the bottom wall of the chamber 6 in the closure plug 5. The tube 13, at a suitable distance above the upper extremity of the tube 10, 85 is formed with one or more openings 15, while the lower end of the tube normally projects below the openings 12 in the tube 10 and so prevents the flow of fluid from the tank through the openings 12 into the sup- 90 95 100

ply pipe 3. The upper extremity of the tube 13 within the chamber 6 is knurled as 16 and formed with a non-circular portion 17 whereby a wrench may be applied 5 to the tube to rotate the latter when necessary.

In practice, the tube 13 is rotated and owing to the connection between the upper portion of such tube and the bottom wall of the chamber in the closure plug the lower end of the tube descends and closes the openings 12 in the tube 10, thereby cutting off communication between the tank and the carbureter by way of such openings. The tank is now filled and the screens 8 act to prevent any sediment or dirt entering the tank. Succeeding the filling of the tank the cap 9 is screwed in place thereby closing the filling opening. As long as the level of the liquid is above the plane of the openings 15 in the tube 13, such liquid will feed through the openings 15, axially alining tubes 13 and 10 and supply pipe 3, to the carbureter or other vaporizing device of the hydrocarbon engine. When, however, the level of the liquid within the tank drops below the openings 15, the supply to the engine is cut off, thereby stopping the engine and advising the operator that the fluid within the tank has dropped below the prescribed point. The operator now removes the cap 9 and rotates the tube 13 with the effect to elevate the latter and so uncover the openings 12 in the tube 10 so that the quantity of fuel trapped in the bottom of the tank will feed through the openings 12, bottom portion of the tube 10 and supply pipe 3 to the engine. The distance between the openings 15 and the bottom of the tank is such that the quantity of liquid retained in the tank is sufficient to reach a point of supply previous to the fuel within the tank becoming exhausted.

In the modified form of my invention illustrated in Fig. 2, I employ a single vertical tube 18 having the lower end thereof screw threaded as at 19 and passed through the outlet opening 2 and threaded into the adjacent end of the supply pipe 3. Formed in the tube 18 below the bottom wall of the reservoir are one or more openings 20, while formed in the tube at a suitable distance above the bottom wall of the reservoir are one or more openings 21. The upper end of the tube 18 passes through the opening 7 in the bottom wall of the chamber 6 in the closure plug 5 and the outer surface of such tube frictionally engages the wall of the tube 10. The tube 18 adjacent to the lower opening. The tube 18 adjacent to the lower end thereof is formed with an outwardly projecting circumferential flange 22 designed to engage the adjacent portion of the bottom wall of the tank when the tube is threaded into the supply pipe so as to limit the downward movement of the tube and

form an effective fluid tight joint at this point.

If desired, the lower end of the tube 18 may be passed through the opening 2 and into the pipe 3 and frictionally engage the latter, as illustrated in Fig. 3.

In the use of the tube 18, the latter is passed through the opening 2 and the apertures or openings 20 in the lower end of the tube disposed below the bottom wall of the tank. Under normal conditions, the liquid within the tank flows through the openings 21, tube 18 and supply pipe 3 to the carbureter or other vaporizing device of the hydrocarbon engine. When the level of the liquid within the tank drops below the openings 21, the supply to the engine is cut off, thereby stopping the latter and advising the operator that the fuel within the tank has dropped below the openings 21. The tube 18 is now rotated with the effect to elevate the openings 20 in the lower end thereof above the bottom wall of the tank so that the quantity of fuel trapped in the tank will feed through the openings 20, bottom portion of the tube 18 and supply pipe 3 to the engine.

From the foregoing description taken in connection with the accompanying drawing, the construction and manner of employing my improved fluid level indicator will be readily apparent. It will be seen that I have provided a fluid level indicator whereby a portion of the liquid fuel within the supply tank of the hydrocarbon engine will be trapped and the operator of the motor vehicle, boat or the like automatically advised when the fluid supply has dropped to a predetermined point and whereby the trapped portion of the liquid fuel may be fed to the engine in order that the vehicle or water craft may reach a point of supply.

While I have herein shown and described certain preferred forms of my invention by way of illustration, I wish it to be understood that I do not limit or confine myself to the precise details of construction herein described and delineated, as modification and variation may be made within the scope of the claim without departing from the spirit of the invention.

I claim:

In a reserve supply valve, the combination with a tank having an outlet opening in the bottom wall thereof and a filling opening in the top wall thereof alining axially with the outlet opening, of a plug closing said said outlet opening, of a chamber filling opening and formed with a chamber having the lower wall thereof within the tank formed with a threaded opening alining axially with the outlet opening in the tank and the side wall thereof formed at diametrically opposite points with openings, filtering screens within said openings, a cap threaded into the upper end of said cham-

1,132,350

ber and removable therefrom whereby the liquid may be poured into the tank, a tube having the lower end thereof disposed within said outlet opening and formed with an opening adjacent to the lower extremity thereof above said outlet opening and having the upper end thereof passed through the opening in the bottom wall of said chan-

ber and threadedly engaging the wall of each opening.

In testimony whereof I affix my signature in presence of two witnesses.
